UNITED STATES PATENT OFFICE.

EMIL JAGENBERG, OF DUSSELDORF, GERMANY.

MACHINE FOR MAKING PAPER BOXES.

No. 848,656.

Specification of Letters Patent.

Patented April 2, 1907.

Application filed April 14, 1905. Serial No. 285,534.

To all whom it may concern:

Be it known that I, EMIL JAGENBERG, a subject of the German Emperor, residing at Dusseldorf, Germany, have invented new and useful Improvements in Machines for Making Paper Boxes, of which the following is a specification.

This invention relates to a machine for folding and pasting the creased blanks of angular paper boxes of the class which are laid into a folded shape during their manufacture.

In the accompanying drawings, Figure 1 is a side elevation of my improved machine for folding and pasting paper boxes. Fig. 2 is a plan thereof; Fig. 3, a detail vertical section through the folding mechanism; Fig. 4, a plan of Fig. 3. Figs. 5 and 6 are details of the folders.

The letter *a* indicates the driving-pulley of the machine, the shaft *b* of which is inter-gearred with a series of pressure-rollers *d*. One of the latter carries a disk *e*, which by a belt or otherwise drives roller *f*. This roller serves to impart motion to an endless elastic feed-apron *g*, by means of which the blanks are carried forward. Above the apron *g* is arranged a perforated guide or core plate *i*, between which and the apron a passage for the blank is formed, such blank projecting laterally beyond the plate. The plate *i* is provided with an eye *i*², that is clamped to a transverse rod *s*, so that the plate is laterally adjustable thereon. To the latter is secured a lever *l*, which is drawn downward by a spring *2*. This spring tends to turn the rod *s* in the direction of the arrow, Fig. 3, so that plate *i* is held with considerable pressure against the apron. Within the openings of plate *i* are journaled a number of guide-rollers *i'*, which are adapted to engage the central portion of the blank. The plate *i* is flanked by a pair of folders *k* *k'*, having curved flanges which are so profiled that they first turn up the sides of the blank and then successively fold them against the top of the plate. Folder *k* is longer than folder

k' and projects with its working or forward end beyond the latter, Fig. 4, so that folder *k* engages one side of the box and starts to turn the same down before folder *k'* engages the opposite side of the box. In this way the ends of the box, which have been previously provided with a layer of adhesive, are made to overlap. After clearing the folders *k* these overlapped ends are subjected to the pressure of a spring-influenced roller *h*, journaled in a bearing *p*, that is laterally adjustable upon a transverse rod *o*. By the lateral adjustment of bearing *p* and roller *h* the latter may be alined with the glued strip of blanks of different widths. From roller *h* the folded blank passes between the rollers *d* and an upper coöperating set of rollers *d'*, by which the folded blank is compressed. The upper rollers *d'* are journaled in hinged arms *6* *6'* to permit the rollers to be readily cleaned.

Having now fully described my invention, what I claim as new, and desire to secure by Letters Patent, is—

1. In a machine for making paper boxes, a pair of folders having curved flanges of different lengths, a feed-apron intermediate the folders and overlapped by the folder-flanges, a pivoted core-plate having an eye and a central row of openings, a rod embraced by the eye; rollers journaled in the openings and adapted to engage the central portion of the blank, and means for pressing the rollers against the blank, substantially as specified.

2. In a machine for making paper boxes, an endless elastic feed-apron, combined with a superposed guide-plate having a series of openings and an eye, rollers journaled in the openings, a rod embraced by the eye, a lever projecting from the rod, and means for depressing the lever, substantially as specified.

Signed by me at Dusseldorf, Germany, this 3d day of March, 1905.

EMIL JAGENBERG.
